UNITED STATES PATENT OFFICE.

LOUIS K. JOHNSON, OF BROOKLYN, ASSIGNOR TO THE ALDEN TYPE
MACHINE COMPANY, OF NEW YORK, N. Y.

COMPOSITOR'S TYPE-CASE.

SPECIFICATION forming part of Letters Patent No. 336,646, dated February 23, 1886.

Application filed July 28, 1884. Serial No. 138,920. (No model.)

To all whom it may concern:

Be it known that I, LOUIS K. JOHNSON, a citizen of the United States, residing in the city of Brooklyn, in the county of Kings and 5 State of New York, have invented certain new and useful Improvements in Compositors' Type-Cases, of which the following is a specification.

My present improvements relate to that 10 class of compositors' type-cases which consist of a suitable number of elongated type-holding compartments or reservoirs open at both extremities and inclined in such manner that type distributed into their upper ends will 15 descend through them automatically to their other extremities, from which they may be removed during the operations of setting, the openings at either extremity being adapted to allow the insertion or removal of a type at any 20 angle, as in the application (No. 101,851) for patent heretofore made by me, and I do not seek to cover such construction, broadly. I have found by experience that there are serious objections to the use of such compartment-cases as heretofore made, and my present invention is the result of experiments made to 25 obviate these difficulties. For instance, owing to the straight unobstructed channel formed by each compartment, and to the steepness of the angle at which it is necessary to arrange 30 them in order to insure the prompt automatic descent of the types, there is danger of the latter overflowing the supporting-shoulders at their lower extremities when the compartments are heavily charged with type. Again, 35 for a similar reason when the compartments are wholly or partially empty, there is danger that the earlier types distributed into their upper ends will descend too rapidly, and striking the supporting-shoulder at the bottom, rebound therefrom out of the case. Whether 40 this happens or not, the type is under such circumstances liable to be more or less battered and damaged by its too rapid descent.

Another objection is that in rapid and careless distribution the types are apt to be thrown into a compartment at such an angle that they will descend therein a considerable distance before encountering the floor, from which, under such circumstances, they are liable to re-

bound against the upper side of the compartment, and so on continuously downward.

If the types are dropped gently through the openings at the upper ends of the compartments, so that they fall upon the floors immediately, they descend upon the latter steadily and safely, and it is the object of one portion of my invention to secure this result.

My invention consists in providing the compartments at their upper ends with receiving-channels or bottomless boxes which coincide with and form continuations of the type-channels, but which occupy with relation thereto an obtuse angle, being vertical, or nearly so, in position, so that types dropped therein must necessarily encounter the floors of the compartments underneath at points near the upper extremities of the latter and within and corresponding to the area of such receivers above.

Another feature of my invention consists in providing the lower front extremities of the compartments above the type-supporting shoulders with either permanent or movable guards or gates, which enter into and contract 75 the type-channels at this point, so as to partially support and retard the type and regulate its descent to the type-supporting shoulders. By this construction I am enabled to successfully use compartments of comparatively larger area and capacity without danger of overflowing, the size of the aperture being necessarily limited by and bearing certain definite proportions to the standard size of the type. These guards also perform another important function, owing to the partial support they afford the columns of type above, in that they relieve the forward or more exposed types on the supporting-shoulders entirely 80 from pressure, so that they may be more easily 85 and quickly picked up and removed in setting.

In the accompanying drawings, Figure 1 is a front elevation of a portion of a compositor's type-case embodying my improved construction; and Fig. 2, a vertical section of the same upon plane of line $x x$, Fig. 1. Fig. 3 is a top view of the same.

Any suitable number of the compartments A A are combined together, according to the 100

number and denominations of the types to be accommodated in a single case. They may be mounted adjustably upon a standard, so that their inclination may be varied in the same 5 manner as my improved type-cases heretofore patented; or, the appropriate angle having been ascertained, they may be supported upon a permanent frame or standard, in the manner of the old form of compositor's type case. 10 These compartments A A are formed with the type-supporting shoulders $a a$ at their lower extremities. The shallow cups or type-presenters a' , thus formed by the supporting-shoulders a and the continuations $a' a'$ of the side 15 walls of the compartments, are designed to expose a sufficient quantity of type loosely before the compositor. For this reason the lower ends of the compartments may all end substantially in the same plane, which plane may 20 be either vertical or inclined with relation to the position of the compositor, as indicated in the drawings. When thus inclined, each cup practically projects slightly in advance of and beyond the extremity of the com- 25 partment next immediately above, bringing all within a uniform distance from the shoulder of the compositor. In like manner, for the purpose of rendering the upper end of the case 30 convenient for distribution, the upper extremities of the compartments are all made to end upon a plane which is horizontal, or nearly so. By thus cutting off the compartments at an angle to their length the area of their open- 35 ings is increased as compared with their area in cross-section, thereby facilitating the operations of distribution. By this construction it will be observed that the lengths of the compartments are gradually and uniformly increased from the top to the bottom of the case. 40 This, far from being objectionable, is convenient and economical of space, since the higher compartments may be devoted to the reception of the "upper-case" type and denominations that are least frequently required, while the 45 lower compartments afford ample room for the accommodation of the comparatively large quantities of "lower-case" types that are required in ordinary composition.

The extreme upper ends of the compartments A A are formed at an obtuse angle to their lengths, the channels turning upward in a vertical or nearly vertical direction. Although this change in the direction of the channels may be effected by making offsets in 50 the compartments themselves, I prefer to accomplish it by the use of an independent top or receiver, B, formed with a series of openings, $b b$, which coincide with and form the mouths or entrances to the inclined type-channels when placed in position upon the top of the compartments. This construction not only 55 has the advantage of cheapness of construction, but it also provides a means of direct access to the inclined channels for the purpose 60 of cleaning, &c. The office of these vertical receiving-channels, as before stated, is to insure the contact of the types dropped therein

with the extreme upper portions of the floors of the inclined channels, and for this reason their height is preferably only sufficient to 70 prevent the introduction of a type through them upon a line parallel with the longitude of the inclined channels beneath.

The guards C, attached to the lower front ends of the compartments, are preferably made 75 so that their lower edges may be adjusted to penetrate more or less into the type channels; but this adjustment is not indispensable, since they may be permanently secured (as indicated upon the upper tier of compartments in 80 the drawings) in an ascertained position—as, for instance, in cases which are designed to be used only for a certain size of type.

The adjustment may be accomplished in a variety of ways, that shown in the drawings 85 consisting in hinging the upper edges of the guards or gates C to the front of the compartments and regulating the penetration of their lower edges into the channels by means of set-screws $c c$, which limit the outward movement 90 of the guards, the latter being free to fall back toward the floors of the channels to the zero-point or lowest position when the latter are empty, or nearly so.

In the construction shown in the drawings 95 the set-screws $c c$ pass through slots or recesses $c' c'$, formed in the guard-plate C, and screw into the division-pieces $a' a'$ more or less, according to the limit to be set upon the forward position of the guards.

1CC

I am aware that elongated type-storing channels formed with parallel sides and of uniform area throughout have heretofore been described, as in the Patent No. 7,738, of October 29, 1850. I am also aware that type-receptacles the upper front walls of which are inclined to form enlarged receiving-hoppers are old, as in the Patent No. 301,909, of July 15, 1884. I do not claim either of these features, broadly; nor are the inclined front walls of the 110 hoppers referred to above the equivalent of my independently-inclined type-guards arranged at the lower extremities of the elongated parallel-sided type storing channels herein described, which channels are adapted to rest 115 one upon another in a series or case, as shown, without loss of space—an arrangement which would not be practicable in the construction shown in the last-named patent.

My independently-inclined guards are specially adapted to, and of importance when used in connection with, the comparatively long parallel channels with which they are herein combined. Without them the channels would be practically useless, owing to the tendency of 120 the types to overflow under the weight of the columns above, the type-supporting shoulders being necessarily reduced to the smallest possible size, in order to conform to and permit of the arrangement of the channels in a compact case or series one above the other.

What I claim as my invention, and desire to secure by Letters Patent, is—

1. In combination with an elongated type-

storing channel formed with parallel walls and of uniform area in cross section throughout the greater portion of its length, and provided with a type-supporting shoulder at its lower extremity, substantially in the manner and for the purpose described, a type-guard situated at the lower termination of the front wall of the channel and inclined inward at an obtuse angle thereto above the said type-supporting shoulder, for the purpose and substantially in the manner described.

2. In combination with an elongated inclined type-storing channel formed with a type-supporting shoulder at its lower extremity, substantially as described, an adjustable guard, substantially such as set forth, arranged at the lower extremity of the channel for the purpose of regulating the descent of the type to the said type-supporting shoulder, substantially in the manner described.

3. An inclined type-containing compart-

ment open at both extremities for the purpose described, formed with a type-supporting shoulder at its lower extremity, and with its extreme upper portion formed at an obtuse angle with relation to the body of the compartment, for the purpose described.

4. The combination, with a series of inclined type-containing compartments combined together for the purpose and substantially in the manner designated, of a removable section containing a series of vertical or nearly vertical type-receiving channels arranged above and coinciding with the upper entrances to the inclined type-channels in the compartments below, substantially in the manner and for the purpose described.

LOUIS K. JOHNSON.
